INKING MECHANISM FOR PRINTING MACHINES

Frederick Lamatsch, Grantwood, N. J., assignor to Irving Trust Company, permanent trustee for R. Hoe & Co., Inc., New York, N. Y., a corporation of New York

Application January 12, 1933, Serial No. 651,295

15 Claims. (Cl. 101—366)

This invention relates to printing machinery and more particularly to printing machines provided with an ink pump and ink rail of the general character described and illustrated in patent 5 of Halliwell, No. 1,589,148, dated June 15, 1926 for inking mechanism.

The principal object of the invention is to provide novel means for maintaining an ink rail in a predetermined variable position for coaction 10 with an ink cylinder, and for adjusting or moving the said rail relatively to the ink cylinder with a view to spreading the amount of ink to be deposited on the latter, while indicating on a micrometer scale the extent of the clearance between the said ink rail and inking cylinder.

Another object is the provision of an ink rail micrometer adjusting mechanism which will obviate the necessity for "feeler" gauges heretofore required.

20 Another object is to provide latch means for retaining an ink rail in inoperative position for cleaning, inspection, etc., with resilient means for returning the ink rail to a fixed position pre-adjustable to the desired point or location.

25 A further object is to provide a combination of means for automatically and accurately registering the distance or clearance between the inking cylinder and coacting ink rail, and automatically operated means for locking the said ink rail in inoperative position so that the latter may be 30 held in fixed position while being inspected, cleaned or adjusted.

35 It is also an object of the invention to provide an ink rail mechanism of generally improved construction, whereby the device will be simple, durable and inexpensive in construction, as well as convenient, practical, serviceable and efficient in its use.

With the foregoing and other objects in view, 40 which will appear as the description proceeds, the invention resides in the combination and arrangement of parts, and in the details of construction hereinafter described and claimed.

The preferred embodiment of the invention is 45 illustrated in the accompanying drawings, wherein:

Figure 1 is a fragmentary elevational view, partly in section, of certain parts of the inking mechanism of a printing machine to which the invention has been operatively applied;

Figure 2 is a fragmentary plan view, partly in section, showing the left end of the device, the ink rail being held in inoperative position by the latch means employed;

50 Figure 3 is a view similar to Figure 2 but show-

ing the right end of the device with the ink rail in operative position; and

Figure 4 is an elevational view, partly broken away, showing the relation and disposition of certain details of the construction including the manually operable ink rail shifting means, the micrometer indicating means, and the latches for maintaining the ink rail in inoperative position.

In the drawings of the preferred form of the 10 invention, the numerals 11 and 11' indicate generally the frame members of a printing machine on which an ink cylinder 12 and the coacting ink rollers 13, 14 and 15 are suitably mounted.

In accordance with the present invention, an 15 ink rail 16 is provided with supporting members or feet 17, 17' which are arranged on trackways 18, 19 secured to the said frame members 11 and 11' of the printing machine. The ink rail 16 is resiliently held in operative position adjacent 20 the ink cylinder 12 by springs 21, the ends of which are connected to the ink rail 16 and frame members 11 and 11' in any suitable manner as by the eye bolts 22, 23, as best shown in Figures 2 and 3. The springs 21 may be adjusted to 25 the tension desired by means of nuts 23' threaded on the bolts 23, it being understood that the normal action of the springs 21 will tend to draw the ink rail 16 towards the cylinder.

A pair of manually operable members 24, for 30 shifting the ink rail 16, are secured on a bar or shaft 25, supported by arms or brackets 26, 27 attached to the frame members 11 and 11' in any suitable manner. The shaft 25 is confined against longitudinal movement by one of the 35 members 24 and a collar 25'. The members 24 are each formed with a pocket 24' for the reception of a suitable tool or key, and are also formed with a notched or forked extension 28 which individually receives a pin 29 fastened to the ink 40 rail 16, whereby when the said members 24 are rocked or angled, the ink rail 16 with its ink outlet bar 18' will be slid towards and from the ink cylinder 12 to a predetermined point or clearance distance from same, effective for depositing the 45 amount of ink desired or necessary.

The means for adjusting the ink rail so that it 50 may be initially adjusted to a desired clearance from the ink cylinder and to insure that it will return to the position desired, includes a pair of adjusting screws 31, threadedly secured to the ink rail 16 and provided at one end with an adjusting or manipulating head 32 and at another with an indicator or pointer 33 which travels over 55

a calibrated plate or scale 34 fastened to the ink rail 16.

Each of the screws 31, the heads 32 of which are adapted to abut against a portion of the stationary frame members 11 and 11' when the ink rail 16 is returned to operative or juxtaposed position relatively to the ink cylinder 12, is also provided with a lock nut 35 which is adapted to abut against a portion of one of the adjacent 10 feet 17, 17' for fixing the said screws 31 in the position desired, the indicator 33 meanwhile, when the screws are turned, denoting on the scale 34 the extent of longitudinal movement of the said screws 31 relatively to the ink rail 16 15 and, consequently, the extent of clearance of the ink rail 16 from the ink cylinder 12, so that the inner end of the screws 31 by protruding to a greater or less extent from the ink rail will determine the degree of adjustment desired. It 20 will now be understood that when the indicator 33 is at the zero point on the scale 34, the ink rail 16 will be in actual contact with the ink cylinder. When the indicator is in the position shown in Figure 4, the said ink rail 16 will have 25 been moved to a definite clearance or distance from the ink cylinder for the passage or spreading of ink on the latter.

By preadjusting the extent of clearance between the ink rail and ink cylinder when in co-30 operative relation, the spreading of the ink on the ink cylinder may be accurately controlled or graduated so that when it is desired to print, for example, many lines arranged in close relation, the ink rail 16 will be initially adjusted to 35 a position or clearance distance from the ink cylinder sufficient to insure the proper spreading of the requisite amount of ink. The said ink rail after the initial adjustment will be fastened in the desired position by the T-bolts 41. For more 40 open printing where less ink is required, the ink rail will be initially adjusted to a clearance distance from the ink cylinder less than that required for close printing.

In order to hold the ink distributing rail or 45 bar 16 when cleaning or inspecting same, locking means are provided which includes a pair of latches 36 each of which are swingingly mounted on a pin 37 secured to the frame 11 and having a tongue 38 which latter is adapted, when 50 the ink rail 16 is in the operative position shown in Figure 3, to rest upon the foot of the said ink rail. When the ink rail 16 is shifted to the inoperative position shown in Figure 2, the tongues 38 drop down between the adjacent portion 55 of the frame members 11 and 11' and the supporting members 17, 17' of the ink rail 16 to the position shown in full lines in Figure 2 and in dotted lines in Figure 4.

The feet 17, 17' of the ink rail 16, as best 60 shown in Figures 2 and 3, are provided with portions having guide slots 39 riding on T-bolts or adjusting members 41, threadedly engaged with the frame members 11 and 11', whereby the ink rail 16 may be locked in operating position, and 65 by unscrewing the said T-bolts to release the feet 17, 17' may be moved or adjusted to the desired position or clearance from the ink drum. The T-bolts 41 are then tightened, thus locking the ink rail in the operating position selected.

70. The function and general manner of operation of the device, in part indicated by the foregoing description, may be summarized as follows:

Assuming it is desired to move the ink rail 16 from the operative position shown in Figures 1 75 and 3, to the inoperative position illustrated in

Figure 2, for inspection, repairs, etc., the T-bolts 41 will be unscrewed, and then the manually operable members 24 will be manipulated, thereby moving the ink rail 16 against the tension of springs 21 to the inoperative position shown in 5 Figures 2 and 4, the latches 36 now falling into the space between the supports 17, 17' of the ink rail 16 and the adjacent portion of the frames 11 and 11' as mentioned above.

Should it be desired to bring the ink rail 16 10 closer to the ink drum 12 for operative coaction therewith, a suitable tool such as a spanner wrench may be applied to the heads 32 of the screws 31 and the said screws turned to the desired extent. This will cause the said screws 31 15 to move further into the ink rail 16 and, consequently, will permit the ink rail 16 to approach closer to the ink cylinder 12, as the springs 21 urge the ink rail 16 forwardly toward the ink cylinder. 20

When adjusting the ink rail to provide more clearance between the said rail and ink cylinder 12, the screws 31 will be turned so that the head 32 of each screw contacts the adjacent portion of the frame 11, thus thrusting the ink rail in 25 a direction away from the ink cylinder, against the resistance of the springs 21, until the clearance distance desired is obtained.

It will be evident that in all cases after the ink rail has been moved to an inoperative position for any desired purpose, the springs 21, after the locking means, hereinbefore described, have been raised, will return the ink rail 16 to the position previously obtained; i. e., where the heads 32 of the adjusting screws 31 abut against frame 35 members 11 and 11'. The extent of the clearance distance between the ink rail and ink cylinder will be accurately denoted by the indicating means 33, 34.

The present method not only insures the return 40 of the ink rail to the operative predetermined position while indicating on a micrometer scale its degree of clearance from the ink cylinder 12, but it also eliminates the necessity for "feeler" 45 gauges or analogous elements which hitherto were deemed requisite for accurately indicating the position of the ink rail relatively to the ink drum.

It will be understood that the invention may be embodied in other specific forms without departing from the spirit or essential attributes thereof, and it is therefore desired the present embodiment be considered in all respects as illustrative and not restrictive, reference being had to the appended claims rather than to the foregoing description to indicate the scope of the invention. 55

What I claim is:

1. In an inking mechanism for a printing machine, an ink cylinder, an ink distributing bar, 60 means for urging the bar towards the cylinder, and stops carried by the bar and adjustable to regulate the amount of clearance between the bar and the cylinder, and means for indicating the degree of adjustment. 65

2. In an inking mechanism for a printing machine, an ink cylinder, an ink distributing bar, resilient means for urging the bar towards the cylinder, stops adjustable to regulate the amount of clearance between the bar and the cylinder, 70 and micrometer indicators on the adjustable stops for denoting the extent of clearance between the said bar and the said cylinder. 75

3. In an inking mechanism for a printing machine, an ink cylinder, an ink distributing bar, 75

- resilient means for urging the bar towards the cylinder, stops adjustable to regulate the amount of clearance between the bar and the cylinder, micrometer indicators on the adjustable stops 5 for denoting the extent of clearance between the said bar and the said cylinder, and means for automatically locking the ink rail in inoperative position.
4. In mechanism of the character described 10 having an ink rail and a coacting ink cylinder, the combination of means for adjusting said ink rail relatively to said cylinder, with means for simultaneously indicating the degree of adjustment, and resilient means for moving the said ink rail to a predetermined position of same, operative for depositing ink on said drum.
5. In mechanism of the character described including an ink rail and a coacting ink drum, the combination of tensioning means for maintaining said ink rail in accurate juxtaposition to the ink drum, means for moving the said ink rail to a position variable with respect to said ink drum, indicating means for showing the extent of movement made by the ink drum, and other 20 means for locking said ink rail in inoperative position.
6. In a device of the character described, the combination of a frame, an ink rail slideable on the frame, an ink cylinder rotatably mounted 25 on the frame, tensioning means connected to the frame and ink rail for returning said ink rail to a predetermined variable position, and latch means automatically operative for locking the said ink rail in inoperative position.
7. In mechanism of the character described 30 having an ink rail, a frame, and an ink cylinder, said ink rail being slidably secured to said frame; adjustable spring means secured to the ink rail and frame for exerting a tension effective to maintain the ink rail accurately juxtaposed to the ink cylinder in a predetermined position, means for varying the position of the ink rail with respect to the ink cylinder, and other means for indicating the degree of clearance of said 35 ink rail relatively to said ink cylinder.
8. In mechanism of the character described having a frame, an ink rail and an ink cylinder mounted on said frame, resilient means for urging and maintaining the ink rail into juxtaposed 40 position relatively to the ink cylinder, adjustable means connected to the ink rail for locating the ink rail in a predetermined variable position, and latch means for locking the said ink rail in inoperative position.
9. In mechanism of the character described 45 having a frame, an ink rail and an ink cylinder mounted on said frame, manually operable means pivoted on said frame and having a connection with said ink rail for moving the ink rail from the ink cylinder to an inoperative position, screw threaded means for varying the position of the ink rail relatively to the ink cylinder to graduate the amount of ink to be applied on said ink cyl- 50
- inder by said ink rail, a micrometer adjustment for locating the ink rail in a predetermined variable position, and means for locking the ink rail in inoperative position.
10. In mechanism of the character described 55 having a frame, an ink rail and an ink cylinder mounted on said frame, manually operable means pivoted on said frame and having a connection with said ink rail for moving the ink rail from the ink cylinder to an inoperative position, and micrometer adjusting means for arranging the ink rail in various desired positions for coaction with the ink cylinder so that the amount of ink deposited by the ink rail on the ink cylinder may be evenly distributed.
11. In an inking mechanism for a printing machine including a frame, an ink cylinder, an ink distributing bar, movable adjusting members carried by the bar independently of the frame and coactable with the frame to thrust the said 20 bar away from the ink cylinder to a position effective for properly spreading ink on same, means for indicating the degree of movement of the adjusting members, and means to return the bar from an inoperative position to said effective position.
12. In an inking mechanism for a printing machine including a frame, an ink cylinder and an ink rail, stop members connected to said rail and coactable with said frame for thrusting the ink 25 rail away from the ink cylinder to a predetermined variable clearance distance effective for spreading ink on said ink cylinder, means for moving the ink rail to an inoperative position, means for locking the ink rail in said inoperative 30 position, and resilient means for returning the ink rail from the inoperative position to the effective clearance distance.
13. In mechanism of the character described 35 having a frame, an ink rail and an ink cylinder mounted on said frame, resilient means for urging and maintaining the ink rail into juxtaposed position relatively to the ink cylinder, and adjustable means carried by the ink rail for locating the ink rail in a predetermined variable position, and means for indicating the degree of adjustment of the adjustable means.
14. In an inking mechanism for a printing machine, an ink cylinder, an ink distributing bar, resilient means for urging the bar towards the 40 cylinder, stops threadedly secured to the bar and adjustable to regulate the amount of clearance between the bar and the cylinder, and means for locking the stops to the bar in adjusted positions.
15. In an inking mechanism for a printing machine including a frame, an ink cylinder, an ink distributing bar slidably mounted on the frame, stops threadedly secured to the bar and adjustable to engage the frame to regulate the amount of clearance between the bar and the cylinder, and means for locking the stops to the bar in its adjusted positions.

FREDERICK LAMATSCH.
